TERMINAL BOARD

Joseph J. O'Hearn, Aurora, N.Y., assignor to General Products Corporation, Union Springs, N.Y., a corporation of New York

Application January 7, 1959, Serial No. 54,070

Term of patent 14 years

(Cl. D26—1)

Fig. 1

Fig. 2

Fig. 4

Fig. 3

Fig. 1 is a perspective view of a terminal board, showing my new design;

Fig. 2 is a side elevational view, the opposite side being substantially a mirror image thereof;

Fig. 3 is a bottom plan view; and

Fig. 4 is a cross-sectional view thereof, taken on line 4—4 in Fig. 2.

I claim:

The ornamental design for a terminal board, substantially as shown and described.
